ALFRED LOUIS BERNARDIN AND GEORGE PETER PFIRRMAN, OF EVANSVILLE, INDIANA, ASSIGNORS TO BERNARDIN BOTTLE CAP CO., OF EVANSVILLE, INDIANA, A CORPORATION OF INDIANA.

PROCESS OF MAKING RECEPTACLE-CLOSURES.

1,370,182.

Specification of Letters Patent.

Patented Mar. 1, 1921.

Application filed June 7, 1919. Serial No. 302,619.

To all whom it may concern:

Be it known that we, ALFRED LOUIS BERNARDIN and GEORGE PETER PFIRRMAN, citizens of the United States, and residents of Evansville, in the county of Vanderburg and State of Indiana, have invented a new and useful Improvement in Processes of Making Receptacle-Closures, of which the following is a specification.

10 Our present invention relates to the art or process of manufacturing closures for receptacles, such as bottles and the like, and among its various objects the invention has for its primary purpose to provide a new and improved process wherein the finished article is formed from a previously lacquered sheet without endangering the mutilation of the lacquered surface, and one which reduces the necessary number of machine operations incident thereto.

15 A further object is the provision of a new and improved process whereby the locking of a cylinder and cap in the formation of the closure may be effected in a single machine operation which serves to rigidly unite the two in locked relation.

20 A still further object is the provision of a process in which the cylinder and its cap, making up the complete closure, are joined, and the other necessary operations performed by pressure applied lengthwise of the cylinder and thus of the complete cap, so as to avoid lateral pressure and the danger of mutilation of the cylinder.

25 With these and other objects as herein-after made plain, our invention resides in the process to be now described with respect to the accompanying drawings, forming a part of this specification, and wherein,

30 Figure 1 is a perspective view of the circular blank for the cap,

Fig. 2 is a cross section through the cap after formation,

35 Fig. 3 is a perspective view of the blank for the formation of the cylinder,

Fig. 4 is a perspective view of the cylinder after formation,

Fig. 5 is a cross section therethrough,

Fig. 6 is a longitudinal section through the cylinder and the cap after their association together,

50 Fig. 7 is a sectional view showing the means employed in the step of locking the cap and cylinder.

55 Fig. 8 is a vertical longitudinal section

through the closure after the cap and cylinder have been locked together,

Fig. 9 is a perspective view of the closure showing the same after the formation of the receptacle engaging indentations,

60 Fig. 10 is another perspective view showing the closure after the formation of the annular knurl.

Referring now to these figures, the process initially contemplates the formation of a cap and cylinder respectively from blanks 10 and 11 shown in Figs. 1 and 3, of which the blank 10 is simply a circular disk cut from a previously lacquered sheet, which is then pressed to the form shown in Fig. 2, wherein it will be noted that the cap 12 as formed, is provided with a surrounding flange 13 and a central indented portion 14, both the flange and the indented portion being pressed in the same direction with the latter inside of and in spaced relation to the former, so as to bring about an internal annular recess to receive one edge of the cylinder as hereinafter described at one end thereof.

65 The blank 11 from which the cylinder 15 is formed, is provided with reduced ends 16 as seen in Fig. 3 and is cut in the shape shown from a previously lacquered sheet and then bent to cylindrical form, the reduced ends 16 being bent to form relatively engaging lips 17 which when pressed form an interengaging seam as seen in Fig. 5.

70 In the operation of bending the blank of Fig. 4 is formed, is provided with reduced ends 16 as seen in Fig. 3 and is cut in the shape shown from a previously lacquered sheet and then bent to cylindrical form, the reduced ends 16 being bent to form relatively engaging lips 17 which when pressed form an interengaging seam as seen in Fig. 5.

75 The blank and forming the cylinder 15, the latter is preferably reduced or drawn inwardly at one end as seen at 18 in Fig. 4 so that when the cap is telescoped upon this reduced portion 18, with the cap flange 13 surrounding the reduced portion, the external diameter of the cap and of the major portion of the body of the cylinder 15 will coincide as seen in Fig. 6. This operation of associating the cap and cylinder together is preferably carried out by hand and results as shown in the extension of the indented portion 14 of the cap within the respective end of the cylinder. The next and final step as far as necessity is concerned is the locking of the associated cap and cylinder, which is 80 accomplished by simultaneously drawing in the reduced end of the cylinder 15 and expanding the inner portion of the cap into locking engagement. To accomplish this step in the process the associated cap and 85

cylinder of Fig. 6 are disposed upon a post 19 as seen in Fig. 7 whose upper end is of the configuration of the inner surface of the finished closure and then applying pressure 5 lengthwise of the cylinder by means of a punch 20 a portion of which encircles the cylinder on the post, so that the central portion of the cap is pressed outwardly and the respective end of the cylinder 10 drawn inwardly, thus forming an opening at one end of the cylinder within which a fold 21 of the cap remains and is expanded to a diameter greater than that of the opening at the indrawn end of the cylinder. 15 Thus with these parts firmly pressed together as seen in Fig. 8 a neat, efficient lock is completed in but a single machine operation and wholly by pressure applied lengthwise of the cylinder.

20 It is desirable that, in the preceding step, the opposite end of the cylinder 15 be formed with a surrounding bead 22 so as to avoid a raw edge for which purpose the post 19 and punch 20 coöperate as will be 25 seen in Fig. 7.

The cylinder with the cap locked thereon is then provided with an annular series of indentations 23 therearound adjacent to its beaded edge 22, to serve as receptacle 30 engaging members and may also be provided with an annular knurl 24 as seen in Fig. 10, it being obvious that these last two formations, namely the indentations 23 and knurl 24, may be accomplished either by lateral 35 pressure or by rolling and either in separate operations or simultaneously and it is furthermore obvious that the knurl 24 at least may be eliminated if so desired.

In any event it is obvious the process as 40 provided by our invention accomplishes the formation and locked association of the parts in but three machine operations, of which particular attention is drawn to the third and final operation wherein the respective end of the cylinder is simultaneously 45 drawn inwardly with the expanding of the central portion of the cap so that it is not only accomplished by a single machine operation, but is brought about without 50 the necessity of lateral pressure and thus without danger of mutilation of any portion of the cylinder as well as without impairment of its original lacquered finish.

We claim:—

55 1. The herein described process of making a receptacle closure which consists in forming a cylinder and a flanged cap separate from one another, telescoping the flanged cap externally upon one end of the cylinder, and then simultaneously constricting 60 the said end of the cylinder and pressing a portion of the cap against the inner surface of said constricted end of the cylinder and thus clamping the latter between 65 the pressed portion and said external flange.

2. The herein described process of making a receptacle closure which consists in forming a cylinder and a flanged cap separate from one another, telescoping the flanged cap upon one end of the cylinder 70 and then simultaneously drawing in the cap flange and the adjacent edge of the cylinder and expanding the central portion of the cap within the cylinder to a diameter greater than the opening formed by the 75 drawn edge of the cylinder.

3. The herein described process of making a receptacle closure which consists in forming a cylinder, then forming a cap with a surrounding flange and a central indented portion extending in the direction of the flange, telescoping the flanged cap on one end of the cylinder and then simultaneously drawing in the said end of the cylinder and expanding the indented portion of the cap within the indrawn cylinder end.

4. The herein described process of making a receptacle closure which consists in providing a cylinder of suitable material, 90 associating a flanged cap externally around one end of the cylinder and then locking the cap and cylinder by simultaneously expanding a portion of the former and constricting a portion of the latter, through the use of pressure applied wholly in the direction of 95 the length of the cylinder to clamp the constricted portion against the external flange.

5. The herein described process of making a receptacle closure which consists in providing a cylinder of suitable material, associating a flanged cap with one end of the cylinder, and then locking the cap and cylinder by reducing the diameter of the said 100 end of the cylinder and expanding the central portion of the cap to a diameter greater than that of the reduced diameter of the cylinder end.

6. The herein described process of making a receptacle closure which consists in providing a cylinder of suitable material, associating a flanged cap in telescoping relation around one end of the cylinder and then locking the cap and cylinder together by simultaneously drawing in the said end of 110 the cylinder and expanding a portion of the cap within the indrawn cylinder end.

7. The herein described process of making a receptacle closure which consists in providing a blank with reduced ends, forming a cylinder of the said blank and bending the reduced ends of the blank to form an interengaging seam at one side of the cylinder, associating a flanged cap in telescoping relation upon one end of the cylinder and then simultaneously drawing in the said end of the cylinder and expanding a portion of the cap within the indrawn cylinder end.

8. The herein described process of making a receptacle closure which consists in

- forming a cylinder of suitable material and simultaneously reducing the same at one end, associating a flanged cap in telescoping relation with the said reduced end of the cylinder and then locking the cap and cylinder by simultaneously drawing in the edge of the cylinder at its reduced end and expanding the central portion of the cap inwardly beyond the indrawn edge of the cylinder.
- 5 9. The herein described process of making a receptacle closure which consists in forming a cylinder and simultaneously reducing one end thereof, associating a flanged cap in telescoping relation with the said reduced end, and in then forming a bead around the opposite end of the cylinder and locking the cap and cylinder by simultaneously drawing in the reduced end of the cylinder and expanding the central portion of the cap within said reduced end.
- 10 10. The herein described process of making a receptacle closure which consists in providing a cylinder of suitable material, forming a cap with a surrounding flange 25 and a central indented portion extending in
- the same direction as the flange, associating the cap in telescoping relation upon one end of the cylinder with its indented portion extending into the cylinder and then locking the cap and cylinder by simultaneously drawing in the said end of the cylinder and pressing the indented portion of the cap outwardly to form an annular expanded lip within the indrawn cylinder end.
- 15 11. The herein described process of making a receptacle closure which consists in providing a cylinder of suitable material, in forming a cap and associating the same with one end of the cylinder so that portions of the cap extend within and without the adjacent cylinder edge and in then locking the cap and cylinder by simultaneously drawing in the said cylinder edge with that portion of the cap outwardly beyond the cylinder edge and expanding the cap so as to increase 40 the diameter of its portion within the cylinder to a diameter greater than the indrawn cylinder edge.
